(57) **CLAIM**

The ornamental design for a vacuum body, as shown and described.

DESCRIPTION

FIG. 1 is a right side elevation view of a vacuum body;
FIG. 2 is a left side elevation view thereof;
FIG. 3 is a front elevation view thereof;
FIG. 4 is a back elevation view thereof;
FIG. 5 is a top plan view thereof;
FIG. 6 is a bottom plan view thereof;
FIG. 7 is a back top right perspective view thereof;
FIG. 8 is a front top right perspective view thereof;
FIG. 9 is a back top left perspective view thereof;
FIG. 10 is a back bottom right perspective view thereof;
FIG. 11 is a front bottom right perspective view thereof;
FIG. 12 is a back bottom left perspective view thereof;
FIG. 13 is a front bottom left perspective view thereof;
FIG. 14 is a close up front bottom right perspective view of FIG. 11 thereof;
FIG. 15 is a close up back top right perspective view of FIG. 7 thereof; and,
FIG. 16 is a close up back top right perspective view of FIG. 7 thereof.

The broken lines are for environmental purposes only and form no part of the claimed design.
The dash-dot lines illustrate the boundary of the enlarged views and form no part of the claimed design.

1 Claim, 14 Drawing Sheets
